UNITED STATES PATENT OFFICE.

WILLIS E. PUTNAM, OF WORCESTER, MASSACHUSETTS.

SASH-OPERATING DEVICE.

Application filed September 2, 1924. Serial No. 735,255.

To all whom it may concern:

Be it known that I, WILLIS E. PUTNAM, a citizen of the United States, residing at Worcester, in the county of Worcester and State of Massachusetts, have invented a new and useful Sash-Operating Device, of which the following is a specification.

This invention relates to a device for operating a sash from the inside.

The principal objects of the invention are to provide a construction for operating a swinging sash which will positively operate the top and bottom of the sash at the same time and to the same degree so that the sash will not receive more pressure at the bottom than at the top and therefore will not have tendency to work out of true after a long period of operation; to provide this means in such form that the sash will have a compound motion and move inwardly at the inner end so that when swung clear out, the window can be washed on both sides from the interior, thus avoiding the necessity of washing it from the outside; to provide simple means for accomplishing these results and an effective guiding means for preventing the sash from binding when it first starts to swing and for forcing it to close tightly.

Other objects and advantages of the invention will appear hereinafter.

Reference is to be had to the accompanying drawings, in which

Fig. 1 is an inside view, partly in section, of a sash and operating device constructed in accordance with this invention;

Fig. 2 is a sectional view on the line 2—2 of Fig. 1, showing the construction of the bottom operating device;

Fig. 3 is a sectional view similar to Fig. 2; but taken on a slightly higher plane and showing the sash wide open; and

Fig. 4 is a sectional view on the line 4—4 of Fig. 2.

The invention is shown as applied to an ordinary window casing 10 and sash 11; but the sash is not hinged directly to the casing. In a recess under the sill is a metal plate 12 located at the side opposite the usual place of pivoting the sash and extending in back under the inwardly projecting part of the sill. To this at a point about half way between the outer and inner side of the window casing is a pivot stud 13 to which is pivoted an arm 14. This arm is curved to enable it to move from the position shown in dotted lines in Fig. 2 to the position shown in Fig.

3, these being the limiting positions. This arm is pivoted to the bottom of the sash at a point 15 at a convenient distance from the inner end 16 of the sash. It is located preferably so as to be pivoted to the under side of the sash and there is enough clearance between the sash and sill to receive this arm 14 which is formed of a flat piece of sheet metal or bar stock and is comparatively thin. A plate 17 is shown screwed to the bottom of the sash for holding the pivot pin 15. A second arm 18 of the same shape, size and location is shown at the top of the sash and frame for independently operating it at the top. These constitute parallel and equal arms for controlling the swinging motion of the sash.

For the purpose of operating the sash I provide a horizontal shaft 20 at the bottom located in a recess 21 back of the casing and projecting out on the inner side and having a crank 22 for turning it. I prefer to terminate the shaft 20 in a hub 26 to which it is fixed. I do this because the length of this shaft varies with the thickness of the casing. I provide the hub with an extension 27 which passes into a hollow casting 23 located in the recess 21. This casting 23 is perforated to receive the shaft extension 21 and is also provided with a larger recess in a box 24 on the end and has a screw plug 25 extending into the boss and constituting a guide for the hub 26 fixed to the shaft 20. On account of the securing of the hub to the shaft it constitutes a continuation of the shaft.

On the extension 27 is fixed a bevel gear 28 meshing with a gear 29 on a shaft 30 at right angles to the shaft 20. The shaft 30 is really an extension of a hub 31 fixed to a screw shaft 32 and passing through a bushing 33 which itself passes through the window casing and screws into a recess in the side of the casing 23 in a similar manner to the hub 25. This screw 32 is supported on the window sill by a brass casting 34 having a bearing for the end of the shaft and obviously will be turned by the turning of the crank 22.

Mesling also with the gear 29 is a gear 36 on a vertical shaft 37 which has a bevel gear 38 on top meshing with a bevel gear 39 on a horizontal shaft 40 driving a screw shaft 42 at the top of the casing. I will not describe the connections between the shaft 40 and the shaft 42 because they are exactly the same as those between the shaft 30 and the

shaft 32. This shaft 42 has a bearing in a bracket 44 depending from the top of the window casing.

All these gears have the same number of teeth but an advantageous leverage is secured by having the gear 29 made with teeth of double length and causing the driving gear 28 to mesh with it at a greater distance from the center than the driven gear 36. Thus, the two shafts 32 and 42 will be rotated at the same speed, although this provides a sort of differential to transmit an excess of power caused by any undue resistance from one shaft to the other and equalize the strain.

The two shafts 32 and 42 are provided with screw threads of opposite pitch but of course the same number of threads to the inch. Each of these is provided with a nut 45 adapted to be moved along the shaft by the rotation of the latter. Each nut is swiveled by a horizontal pin 46 to a bracket 47 of right angular construction to fit around the corner of the sash. The bracket constitutes half of a hinge and has a vertical pivot stud 48 at the outer end of the projecting part which, in turn, is pivoted to a right angle plate 49 constituting the other half of the hinge and secured around the corner of the sash 11. These two pivot studs 48 are in vertical alignment and the two hinges thus formed necessarily operate together and equally. The casing and sash are recessed at 54 to receive the parts 47 and 48. The controlling arms 14 and 18 being constructed exactly alike and located in exactly corresponding positions also help to control the motion of the sash so that it will always move equally at top and bottom. The gear arrangement insures an equalization of strain between the top and bottom and therefore, even after long usage, the two operating mechanisms will continue to operate the sash equally at the top and bottom. Therefore the device is not likely to get strained at either place or to bind.

For the purpose of preventing undue strain on the parts when the window is starting to open, I provide on the stationary part of the sash at the top and bottom a plate 50 having a projection provided with an upward guide 51 which is longitudinal with respect to the closed window and is intended to operate only while the crank handle 22 is being turned to take up any looseness of the gears before the sash begins to turn. It might be explained here that the first motion of this crank moves outwardly the two nuts 45 slightly before the sash can commence to turn. This action takes place during about a quarter of a turn of the crank and it might tend to swing the hinge member 47 and bind the parts if no guide were provided. Also in closing, a perfectly tight closure is difficult to secure at this point for the same rea-

son. Therefore this short guide 51 projects upwardly at the bottom behind the hinge part 47 and insures longitudinal motion at the end of the closing and beginning of the opening motion. Therefore the motion of the nut 45 and its bracket 47 slightly to the left to the position shown in Fig. 2 from that in which it is up against the head of the hub 32 will not bind the sash but will release it. Also it will be noticed that when the sash is closed the outer end of the sash comes up into perfectly closed position but the inner end has a tendency to move outwardly slightly. But during the last quarter turn of the crank 22 this guide 51 comes into action and firmly holds the inner end of the sash in tightly closed position. This construction is formed at the top and bottom and the same reference numerals are applied in both places.

In this way it will be seen that a construction is provided which is not unduly expensive but which will positively actuate the shaft both at the top and the bottom, will positively close it at the pivot edge, keep it closed until the crank is turned, and prevent its moving outwardly at the beginning of the turning of the crank and binding. Furthermore, by the gear arrangement the strains at the top and bottom are equalized and therefore the wear is the same in both places. The window does not swing on a fixed pivot but on a movable one so that it will move along the sash at the pivot end and the sash will be located part way between the two sides of the casing when it is open so that the window can be washed on both sides from the interior of the house.

Although I have illustrated and described only one form of the invention I am aware of the fact that modifications can be made therein by any person skilled in the art without departing from the scope of the invention as expressed in the claims. Therefore I do not wish to be limited to all the details of construction herein shown and described but what I do claim is:—

1. In a sash operating device, the combination with a casing and sash, of two screws located constantly in horizontal position at the top and bottom of the casing for simultaneously and equally moving the top and bottom of the inner edge of the sash away from the adjacent edge of the casing, means for actuating said screws, and means acting directly on the top and bottom of the outer end of the sash for swinging it outwardly.

2. In a sash operating device, the combination with a window casing and sash, of a pair of arms one located above the top of the sash opening and the other below the bottom of the sash opening, both pivoted to the casing at points intermediate the inner and outer surfaces thereof and pivoted

- at their outer ends respectively to the top and bottom of the sash at points adjacent to the inner edge thereof, a pair of hinges, one hinge member of each hinge being fixedly mounted on the inner side of the sash at the top and bottom and extending around the edge of the sash and having a hinge pivot located along the edge of the sash, the other hinge member being connected with the hinge pivot and having a part extending therefrom inwardly toward the inside of the casing and another part at right angles thereto, and means for sliding the latter part along the casing parallel with the front surface thereof.
- 5 5. In a sash operating device, the combination with a casing and sash, of an arm pivoted to both for swinging the sash, a hinge having two members, one fixed to the edge of the sash and the other slidable along the casing, and having an offset at the end at which it is pivoted to the other hinge member on the edge of the sash, a nut swiveled to the sliding part of the hinge, and a screw passing through the nut for operating it.
- 10 6. In a sash operating device, the combination with a casing, a sash and an arm pivoted to both for swinging the sash, of a hinge having two members, one fixed to the edge of the sash and the other slidable along the casing, said members both having an offset at the end at which they are pivoted together by a pivot pin, a nut swiveled to the sliding part of the hinge, a screw passing through the nut for operating it, and a 55 guide plate fixed on the side of the casing and having a hook projecting under the sliding member in certain positions thereof for preventing side play of the sliding member at the time when the sash is closed or 60 nearly closed.
- 15 7. In a sash operating device, the combination with a window casing and sash, of an arm pivoted to the casing and pivoted to the sash, a hinge comprising two members, one being fixedly mounted on the inner 65 side of the sash and extending around the
- 20 8. In a sash operating device, the combination with a window casing and sash, of an arm pivoted to both for swinging the sash, a hinge having two members, one fixed to the edge of the sash and the other slidable along the casing, and having an offset at the end at which it is pivoted to the other hinge member on the edge of the sash, a nut swiveled to the sliding part of the hinge, and a screw passing through the nut for operating it.
- 25 9. In a sash operating device, the combination with a window casing and sash, of an arm pivoted to both for swinging the sash, of a hinge having two members, one fixed to the edge of the sash and the other slidable along the casing, said members both having an offset at the end at which they are pivoted together by a pivot pin, a nut swiveled to the sliding part of the hinge, a screw passing through the nut for operating it, and a 70 guide plate fixed on the side of the casing and having a hook projecting under the sliding member in certain positions thereof for preventing side play of the sliding member at the time when the sash is closed or 75 nearly closed.
- 30 10. In testimony whereof I have hereunto affixed my signature.
- 35

WILLIS E. PUTNAM.
